DESIGN FOR A DISPLAY BOX

Frank W. Matthay, Janesville, Wis., assignor to The Parker Pen Company, Janesville, Wis., a corporation of Wisconsin

Application November 3, 1938, Serial No. 80,847

Term of patent 7 years

To all whom it may concern:

Be it known that I, Frank W. Matthay, a citizen of the United States and a resident of Janesville, in the county of Rock and State of Wisconsin, have invented a new, original, and ornamental Design for a Display Box, of which the following is a specification, reference being had thereto to the accompanying drawing, forming a part thereof, wherein

Figure 1 is a perspective view of a display box in closed position showing my new design, that end of the box not specifically shown being substantially identical with the end that is shown;

Figure 2 is a perspective view of my box in opened position, the cross-sectional shape of the back portion of the box from end to end being similar to the shape of the end shown in the drawing; and

Figure 3 is a diagrammatic end elevational view of the box in opened position, the opposite end not specifically shown being substantially identical with the end disclosed.

I claim:

The ornamental design for a display box, substantially as shown and described.

FRANK W. MATTHAY.
